UNITED STATES PATENT OFFICE.

GEORGE H. WESTON, OF BOSTON, MASSACHUSETTS.

ROTARY ENGINE.

SPECIFICATION forming part of Letters Patent No. 449,148, dated March 31, 1891.

Application filed August 28, 1890. Serial No. 363,299. (No model.)

To all whom it may concern:

Be it known that I, GEORGE H. WESTON, of Boston, county of Suffolk, State of Massachusetts, have invented an Improvement in Rotary Engines, of which the following description, in connection with the accompanying drawings, is a specification, like letters and figures on the drawings representing like parts.

This invention relates to rotary engines and is an improvement upon the engine shown and described in United States Patent No. 426,553, granted to me April 29, 1890.

My present invention has for its object to improve the construction of the engine referred to, whereby the valve may be opened at an earlier period of its stroke.

In accordance with my invention the piston-valve at its port-opening is provided with a longitudinal arm to enter a longitudinal groove or recess in the abutment, whereby the space between the abutment and piston-valve is made steam-tight, thereby enabling the valve to be opened at an earlier period of its stroke or revolution.

Other features of my invention will be pointed out in the claims at the end of this specification.

Figure 1 is a transverse section of a rotary engine embodying my invention, the section being supposed to be taken on line $x-x$, Fig. 2; Fig. 2, a section of the engine shown in Fig. 1 on the line $x'-x'$; Fig. 3, a detail to be referred to, and Fig. 4 a detail of the form of gearing preferred by me.

The cylindrical case A, provided with the bearings a' , the bearing a being extended into the said case and having mounted upon it the abutment a^2 , located within the case A, and the cover a^3 , secured to the said case, are and may be substantially such as shown and described in United States Patent No. 426,553, granted to me April 29, 1890.

The abutment a^2 , herein shown as detachably secured, as by screws a^4 , to the enlarged head a^5 , secured to or forming part of the shaft a^6 , is provided in accordance with my invention with a longitudinal or axial groove, channel, or recess a^7 . (See Figs. 1 and 3.)

The shaft a^6 , as herein shown, is extended through the bearing-sleeve a^8 , made conical at its inner end, as at a^9 . The shaft a^6 is coupled, as shown, by gears $a^{10} a^{12}$ to the shaft

a^{13} , to the enlarged head a^{14} of which is secured, as by screw a^{15} , the piston-valve a^{17} , preferably provided at its front end with the projecting portion a^{18} and at its rear end with the flange a^{19} . The piston-valve a^{17} is provided with a longitudinal slot or port opening b , (see Figs. 1 and 3,) and one wall of the said slot is provided with an extended lip b' , which projects into the groove a^7 and fits therein steam-tight, the said lip extending the length of the said groove or channel. The piston-valve is provided with the arm b^3 , which enters the re-entrant portion b^4 of the abutment, the said arm being made separate from the piston-valve and secured thereto in any suitable manner, as by a screw or bolt b^{10} . By making the arm b^3 separate from the piston-valve I am enabled to employ lighter metal, such as alumina.

The hollow piston-valve a^{17} has co-operating with it the cut-off b^5 , provided with the stem or rod extended out through the cover a^3 , as in the patent referred to. By means of the lip b' entering the groove a^7 and fitting steam-tight therein the piston-valve may be made to open earlier, as the said lip prevents the escape of live steam into the exhaust-port b^8 .

Referring to Fig. 3, the lip b' on the piston-valve is shown in contact with one edge, as 2, of the groove or channel a^7 , and the port-opening or space between the abutment and the piston-valve from the point 3 to the said lip is rendered steam-tight, so that the steam-inlet port of the valve may be opened earlier than if the lip b' was omitted.

Referring to Fig. 4, I have shown the form of gears $a^{10} a^{12}$ preferred by me, the gear a^{10} being provided with teeth a^{20} , having a flat 9c face, as 20, in a radial line with the center of the gear, the said face preferably having fitted into it a buffer 30 of leather or like material. The gear a^{12} is provided with teeth a^{21} , having one side or face, as 4, made curved so that the point of contact of the teeth $a^{20} a^{21}$ is in a direct line with the centers 7 8 of the gears.

By making the arm b^3 of alumina the piston-valve is not thrown so far out of balance, and consequently does not have to be provided with as much counterbalancing metal d^{10} as would be the case if the said arm is made of steel or other heavier metal.

I claim—

1. In a rotary engine, the combination, with an inclosing case provided with a bearing, of an abutment having a re-entrant portion and a groove or channel a^7 on its periphery extended axially, a shaft for said abutment, a piston-valve provided with an arm to enter said re-entrant portion and with a lip b' to enter said groove or channel, and a shaft for said piston-valve, substantially as described.
2. In a rotary engine, the combination, with an inclosing case provided with a bearing, of an abutment having a re-entrant portion and a groove or channel a^7 on its periphery extended axially, a shaft for said abutment, a

gear a^{10} on said shaft, a hollow piston-valve provided with an arm to enter said re-entrant portion and with a lip b' to enter said groove or channel, a shaft for said piston-valve, and a gear a^{12} on said shaft in mesh with the gear a^{10} , the point of contact of the teeth of said gears being in a direct line with the centers of the gears, substantially as described.

In testimony whereof I have signed my name to this specification in the presence of two subscribing witnesses.

GEORGE H. WESTON.
